UNITED STATES PATENT OFFICE.

GEORGE GOLDEN, OF LACKAWANNA, NEW YORK.

BEDSTEAD.

1,240,195.

Specification of Letters Patent. Patented Sept. 18, 1917.

Application filed April 24, 1916. Serial No. 93,193.

To all whom it may concern:

Be it known that I, GEORGE GOLDEN, a citizen of the United States, residing at Lackawanna, West Seneca, New York, in the county of Erie and State of New York, have invented certain new and useful Improvements in Bedsteads, of which the following is a specification.

This invention relates to bedsteads and has for its object to produce a bedstead of simple and improved construction, the mattress supporting frame of which shall be supported upon springs so that a separate bed spring may be dispensed with.

A further object is to provide readily replaceable spring supports for the mattress supporting frame and which are hidden from view when in use.

Still further objects of the invention are to simplify and improve the construction and operation of the class of devices to which my invention refers.

In the accompanying drawings has been illustrated a simple and preferred form of the invention; it being however understood that no limitation is necessarily made to the precise structural details therein, exhibited, but that changes, alterations and modifications within the scope of the invention, may be resorted to when desired.

In the drawings:

Figure 1 is a perspective view of a bedstead made in accordance with the invention.

Fig. 2 is a side elevation showing the normal position of the mattress support in full lines and depressed position in dotted lines.

Fig. 3 is a horizontal sectional view.

Fig. 4 is an enlarged detail horizontal sectional view.

Fig. 5 is an enlarged detail perspective view.

Fig. 6 is an enlarged elevation of one of the bed posts showing manner of removing spring.

Fig. 7 is a detail vertical section of one of the posts.

Fig. 8 is a detail cross section on line 8—8 of Fig. 4 and

Fig. 9 is a detail cross section on line 9—9 of Fig. 4.

Referring more particularly to the drawings in which corresponding parts in the several figures are denoted by like characters of reference, A and B designate respectively the head and foot members of a bed-

stead, constructed in accordance with the invention; the tubular corner posts 1 of said head and foot member being provided with clamps or sockets 2 for engagement with the ends of the side rails 3 whereby said head and foot members are connected. Similar clamps or sockets 4 of somewhat lighter construction are secured to the opposite ends of end rails 5. Further description of the fastenings and end and side rails will be omitted as these parts are old and well known in the art.

The corner posts 1 are identical in construction; therefore a description of one will suffice for all. Each post comprises an open ended tube, connected to the upper end of which is a threaded coupling 6 adapted to receive the ends of upper head and foot cross bars or tubes 7.

Fitting snugly within the upper end of the corner posts is a shouldered plug or cap-piece 8 suspended from which by means of a bolt 9 and strap 10 is a coil spring 11. The lower end of this spring is connected to a strap 14 which in turn supports a depending cylindrical slotted plunger 12 the diameter of which is somewhat less than the diameter of the corner post. To insure a tight fit and thus obviate wobbling the plunger 12 is provided with annular washers 13.

A mattress supporting frame 15 is detachably secured to and supported by corner brackets 16. These brackets are made by bending a strip of sheet metal back upon itself to form a tongue 17 and then spreading the legs 18 to form side and end members 19 and 20 respectively. A pair of L-shaped locking members 21 and 22 pivoted as at 23 and 24 to the side and bottom of the frame 15 holds the latter securely but detachably to the corner brackets 16. The tongue 17 of these brackets is inserted through slot 18' formed in the corner posts and into corresponding registering slot 19 with which the plunger 12 is provided.

It will thus be seen that the entire weight of the mattress supporting frame is resiliently suspended from the springs 11. Preferably a box mattress (not shown) is placed upon the frame 15, but if desirable the ordinary hair or straw mattress may be used. In the latter case it will of course be understood that slats 20' will be employed.

In order to guard against the possibility of vermin entering the slot 18, a segmental plate 25 is provided. This plate is suitably

attached to the lower end of the plunger 12 as at 26, a portion of the lowermost washer 13 being cut away to permit of the plate being properly located so as to bring the 5 slot 27 formed therein, into registry with the slots 18 and 19.

An auxiliary cushioning medium or bumper is also provided comprising a cylindrical shouldered member 28 adapted to be 10 removably inserted in the lower end of the posts upon the upper end of which a coil spring 29 is mounted. This spring limits the downward movement of the plunger 12 and functions as a shock absorber when the 15 spring 11 is subjected to abnormal strain.

Should it be desirable for any reason to remove any or all of the parts inclosed within the posts all that is necessary is to first unscrew the couplings 6 and then remove the plug or cap piece 8 together with the spring 11 and plunger 12. Likewise the cylindrical member 28 and spring 29 may as 20

easily be removed from the post. These parts can thus be readily removed for repair or replacement.

25

Having thus described my invention, what I claim is:—

A bedstead comprising head and foot members each including suitably connected slotted posts, a spring suspension device within said posts, a mattress supporting frame and supporting brackets therefor, said brackets comprising strips bent intermediate their ends to form tongues, said tongues adapted to extend into the slotted posts into engagement with said suspension devices.

In testimony whereof I affix my signature in presence of two witnesses.

GEORGE GOLDEN.
